C. KLAUBERG.
BRUSH FOR CLEANING BOTTLES.
APPLICATION FILED FEB. 10, 1920.

Patented May 10, 1921.

Inventor

Charles Klauberger

By Frederick V. Winters

Attorney

UNITED STATES PATENT OFFICE.

CHARLES KLAUBERG, OF NEW YORK, N. Y.

BRUSH FOR CLEANING BOTTLES.

1,377,690.

Specification of Letters Patent. Patented May 10, 1921.

Application filed February 10, 1920. Serial No. 357,541.

To all whom it may concern:

Be it known that I, CHARLES KLAUBERG, a citizen of the United States, and resident of New York, in the county and State of New York, have invented certain new and useful Improvements in Brushes for Cleaning Bottles, of which the following is a full, clear, and exact specification.

This invention relates to brushes for washing bottles, and has for its object to provide a brush of this type which is of very simple and inexpensive construction but efficient and durable in operation.

A special object is to simplify and improve the pivot connection between the handle shank and brush head, whereby said connection will be strengthened and movement of the brush head on the pivot restricted to the desired extent. Another object is to simplify and improve the structure of the brush head, whereby the face of the brush and the tuft at the end may be formed more readily and cheaply than heretofore. Other objects will appear as the description proceeds.

The invention will be first hereinafter described in connection with the accompanying drawings, which constitute part of this specification, and then more specifically defined in the claims at the end of the description.

In the accompanying drawings, wherein similar reference characters are used to designate corresponding parts throughout the several views:—

Figure 1 is a perspective view of a brush constructed substantially in accordance with this invention.

Fig. 2 is a section through the brush head across the channel portion thereof where the pivot pin connects the handle shank thereto, and

Fig. 3 is a longitudinal section through the brush head, showing more clearly how the brush is attached to the core member.

The brush head 1 is pivotally connected to the end of the handle shank 2 by means of a pin or rivet 3 passed through the channel portion 4 of the core member 10 of said brush head and through a bore 5 formed partly in each of the facing sides of a lapped part 6 at the end of the shank. Said bore

is spaced from the extremity of the shank a distance somewhat greater than the depth of the channel 4 below the pivot, so that said projecting end portion of the lapped part 6 will limit the pivotal movement of the brush head on the shank, as shown best in Fig. 3. When the brush head is straightened out, the shank may lie in the channel 4 which preferably extends at least half the length of the core member 10.

The outer end portion of the core 10 is made tubular, as at 7, said tubular portion extending in line with the channel 4. The brush proper consists of a straight section of cylindrical brush of the type formed by fastening transverse bristles 8 at intermediate points in a twisted wire core 9. A section of such brush is cut to a length greater than the core 10 of the brush head 1 and is attached thereto by bending one end of the wire core 9 over the outside of the brush head core 10 so that it extends into the outer end of the tubular portion 7, while the other end of said wire is bent to lie in the end of the channel 4. The bristles carried by the portion of the wire which extends into the tubular portion 7 are bunched together by the walls of said tubular portion so as to form the end tuft 11 which greatly assists in cleaning the bottoms of the bottles from the inside. As shown in Fig. 2, the bristles of the body portion of the brush almost entirely surround the core 10.

Having thus described my invention, what I claim as new and desire to secure by Letters Patent of the United States is:—

1. In a brush of the character described, the combination with a brush head having a channel portion, of a rigid handle shank having a lapped end portion the adjacent surfaces of which lie flat against each other and the outer surfaces of which are parallel, there being a bore formed partly in each of said lapping portions constituting a pivot bearing, and a pivot pin passed through the sides of the channel and said bearing for connecting the brush and shank.

2. In a brush of the character described, the combination with a brush head having a channel portion, of a rigid handle shank having a lapped end portion the adjacent surfaces of which lie flat against each other

and the outer surfaces of which are parallel, there being a bore formed partly in each of said lapping portions constituting a pivot bearing, and a pivot pin passed through the sides of the channel and said bearing for connecting the brush and shank, said bore being spaced from the extremity of the

shank to provide a stop to engage the base of the channel for limiting the pivotal movement of the brush head on the shank. 10

In testimony whereof I have signed my name to this specification.

CHARLES KLAUBERG.
